UNITED STATES PATENT OFFICE.

MEYER L. ROBBINS, OF NEW YORK, N. Y.

DESIGN FOR A CUT GEM.

44,937.

Specification for Design.

Patented Nov. 25, 1913.

Application filed October 15, 1913. Serial No. 795,216. Term of patent 7 years.

To all whom it may concern:

Be it known that I, MEYER L. ROBBINS, a citizen of the United States, residing at New York city, in the county of New York and State of New York, have invented a new, original, and ornamental Design for a Cut Gem, of which the following is a specification, reference being had to the accompanying drawing, forming part thereof.

Figure 1 is a plan view, Fig. 2 an eleva-

tion and Fig. 3 a side elevation in inclined position, showing my new design.

I claim:—

The ornamental design for a cut gem, as shown.

MEYER L. ROBBINS.
